UNITED STATES PATENT OFFICE

2,684,075

VACUUM BREAKING APPARATUS

Ernest Stossel, San Francisco, Calif.

Application April 17, 1952, Serial No. 282,763

15 Claims. (Cl. 137—103)

1

The present invention relates to a vacuum breaking apparatus. More particularly, the present invention relates to a vacuum breaking apparatus whose pulsations are controlled by a resilient, yieldable diaphragm actuated by changes in volume and pressure of a confined gas.

The device of the present invention is adapted to have a great number of different applications. For example, it may be used with vacuum cleaners in order to produce pulsations; it may be used with cement mixing apparatus in the construction of a building, for example; it may be used in a similar way with road construction apparatus or with apparatus for constructing cement blocks in order to speed the drying time; or it may be used in the plastics industry in connection with the fillings of molds and the elimination of air holes; and the device may similarly be used with the casting of metal.

One of the objects of the present invention is to provide a vacuum breaker which is of an extremely simple construction and easily adaptable for various diverse uses as, for example, those mentioned above. Heretofore it has been necessary to construct vacuum breakers differently depending on the purpose for which they were used. In addition to being constructed differently from the above-mentioned uses, vacuum breakers were constructed differently depending on whether they were to be used with milking machines, automatic bottle filling apparatus, liquid pumps, etc. However the present invention aims to provide a vacuum breaker which may be used for these latter purposes as well as for those mentioned above without any changes in the construction thereof so that it is unnecessary to provide a great number of complicated elements which cause frequent breakdowns.

Another object of the present invention is to provide a means for holding the flexible diaphragm of the vacuum breaker in the vacuum breaking position for a predetermined length of time independently of the differential in gas pressures on opposite sides of the diaphragm.

A further object of the present invention is to provide a vacuum breaker capable of accomplishing the above objects while being fully automatic in operation.

A still further object of the present invention is to provide a means for adjusting the tension in the diaphragm so as to control the pressure at which the vacuum is broken.

Yet another object of the present invention is to provide a means for adjusting the length of time during which the vacuum remains broken.

2

An additional object of the present invention is to provide a removable mounting for the diaphragm so that different diaphragms may be used with the same apparatus.

With the above objects in view the present invention mainly consists of a vacuum breaker having an outer hollow casing formed with an opening passing therethrough for admitting gas to the interior of the casing. Within this casing there is mounted a resilient flexible diaphragm which in one position thereof covers the opening in the casing and in another position thereof uncovers this opening, the diaphragm being spaced at a portion thereof from the casing to form therewith a passage through which gas may enter to the interior of the casing.

A duct communicates with the interior of the casing and is adapted to be connected to a vacuum pump for producing a partial vacuum in the casing, this duct having a free open end located in the interior of the casing adjacent to the diaphragm on the opposite side thereof from the opening in the casing. A gas enclosure having a wall thereof facing the free open end of the duct is joined to the diaphragm and covers the free open end of the duct when the gas in the gas enclosure expands and the diaphragm moves away from the opening in the casing. In this way the duct is closed by the wall of the gas enclosure until the gas therein contracts to permit the duct to become uncovered so that the diaphragm snaps back to the position where it closes the opening in the casing to again prevent the entrance of gas thereto and to permit a partial vacuum to again be produced in the casing by the vacuum pump connected to the duct. Means are provided for adjusting the gas pressure in the gas enclosure, the tension in the diaphragm, and the distance of the free open end of the duct from the gas enclosure so that the pressures at which the diaphragm moves to admit gas to the casing and to prevent the entrance of gas thereto may be easily and accurately regulated.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a sectional elevational view through one possible apparatus for carrying out the present invention;

Fig. 2 is a fragmentary top plan view taken along line 2—2 of Fig. 1 in the direction of the arrows;

Fig. 3 is an illustration of the structure of Fig. 1 in a different position from that shown in Fig. 1;

Fig. 4 is a side sectional view of another embodiment of a construction adapted to carry out the present invention;

Fig. 5 shows the structure of Fig. 4 in a different position from that shown in Fig. 4; and

Fig. 6 shows still another embodiment of the present invention.

Referring now to the drawings, Fig. 1 shows an outer substantially spherical casing 10 formed from two flanged, substantially hemispherical shells 11 and 12 which are clamped together at their flanges, any suitable sealing means, such as a gasket 13 or the like, being located between the flanges of shells 11 and 12 to seal the interior of the casing 10 at the joint between shells 11 and 12. The casing portion 11 is formed with an inlet opening 14, which in the example of Fig. 1 takes the form of a tube 15, and the shell portion 12 is formed with a pair of openings 16 and 17. A threaded tube 18 is permanently connected to the opening 16 and is adapted to be connected to an apparatus with which the device of the present invention is to be used.

An internally threaded member 19 is fixedly connected to the opening 17 and threadedly supports therein a duct 20 which is adapted to be connected to a vacuum pump (not shown) for producing a vacuum in the interior of the casing 10. By means of the threaded connection of duct 20, the position of its free open end 21 in the casing 10 may be adjusted, and this free open end 21 may have a reduced cross-section as compared to the remainder of duct 20, as is illustrated in Fig. 1.

Fixedly mounted on the interior of casing portion 11 is a circular, substantially conically shaped plate 22 having an open end 23 fixedly connected to the bottom of tube 15 on the interior thereof, by means of welding or the like, to form with the tube 15 a tubular means for conveying gas to the interior of the casing 10. The plate 22 is provided with a plurality of apertures 24 none of which are located at the open end portion 23 thereof.

Within the casing 10 on the underside of plate 22 there is located a resilient, flexible diaphragm 25 made of rubber or any other suitable plastic. This diaphragm is fixedly mounted adjacent its periphery on the plate 24 by means, for example, of a ring 26 and a plurality of screws passing through the ring 26, the diaphragm 25 and threadedly engaging threaded openings in the plate 22. The diaphragm 25 is thus movable toward and away from the plate 22 at all points except at a circular portion adjacent the periphery of the diaphragm.

As is shown in Fig. 1, diaphragm 25 has an extension 27 projecting into the interior of tube 15 and resiliently bearing against the open end portion 23 of plate 22 to close the interior of the casing 10 and prevent the admission of gas thereto through the tubular means 15, 23.

A bar 28 (Fig. 2) is fixedly mounted on the top end of tube 15 without closing the latter and is formed with a threaded opening in which a screw 29 is located, this screw having an enlarged bottom end 30 located within a cup-shaped member 31 fixed to the end portion of extension 27 of diaphragm 25 by means of a pin 32. The part

of diaphragm 25 to which pin 32 is connected may be made of a material less resilient than the rest of the diaphragm, in a manner well-known in the art.

The diaphragm 25 is formed with a hollow space 33 covered by a relatively thin, flexible wall 34 joined to the diaphragm and made of the same material as the latter, the wall 34 in the embodiment of Fig. 1 being integral with the diaphragm. Thus, the diaphragm forms with the wall 34 a gas enclosure enclosing a gas which automatically expands and contracts with changes of pressure in the casing 10.

The above described structure operates as follows:

Assuming that element 18 is connected to a device with which the above apparatus is being used and that duct 20 is connected to a vacuum pump, the apparatus with the parts thereof in the position shown in Fig. 1 is in the condition where the diaphragm 25 engages the open end 23 of plate 22 about the entire periphery thereof to seal the tubular means 15, 23 and thereby prevent the entrance of gas into the interior of the casing 10 from the outside thereof. Thus, the operation of the vacuum pump (not shown) connected to the duct 20 causes the gas pressure within the casing 10 to drop, and with this drop in gas pressure the gas within the enclosure 33 will automatically expand and cause the wall portion 34 of enclosure 33 to become distended toward the open end 21 of duct 20.

When the gas pressure within the casing 10 has dropped sufficiently, the pressure differential on the diaphragm 25 will cause the latter to move downwardly, as viewed in Fig. 1, and the suction in duct 20 will contribute to this effect by drawing the distended wall 34 into the opening 21 to cover the latter and seal the duct 20, the suction in the latter maintaining the wall portion 34 over the opening 21 to close the latter, as is illustrated in Fig. 3. When the parts are in the condition shown in Fig. 3, gas from the outside of casing 10 enters through tubular means 15, 23 and openings 24 in the plate 22, some of these openings being located below the diaphragm 25, as viewed in Fig. 1, so that the gas on the outside of casing 10 enters into the latter and causes the gas pressure therein to rise. The diaphragm 25 will be maintained in the position shown in Fig. 3 for a longer time than it would if the apparatus were not provided with the gas enclosure 33 because of the maintenance of wall 34 over the opening 21 by the suction in duct 20. As the gas pressure in the casing 10 rises, the gas in enclosure 33 automatically contracts and the wall portion 34 gradually contracts until it opens the opening 21, at which time the diaphragm 25 snaps back to the position shown in Fig. 1 under the action of the resilient force inherent in the material of the diaphragm.

This latter force may be regulated by the turning of screw 29 which causes the extension 27 of diaphragm 25 to become stretched to a predetermined extent so that the diaphragm will not move from the position of Fig. 1 to that of Fig. 3 until the pressure within the casing 10 falls below a predetermined value, the screw 29 thus serving to adjust the pressure at which the valve formed by parts 23 and 25 will automatically open to admit gas to the interior of casing 10 and cause the pressure therein to rise.

The pressure at which the diaphragm 25 will move from the position shown in Fig. 3 to that shown in Fig. 1 may be regulated by turning duct

26 in the internally threaded fitting 19 so that the open end 21 of duct 20 is located at a predetermined distance from the gas enclosure 33. Thus, when the open end 21 of duct 20 is located relatively near to wall 34, the extension 27 will be tensioned to a relatively low degree and the gas in the enclosure 33 will contract considerably before the tension in wall portion 34 will become sufficiently reduced to cause the opening 21 to become uncovered, so that the pressure at which the diaphragm 25 closes the casing 10 will be relatively high. On the other hand, if the free open end 21 of duct 20 is located relatively far from the enclosure 33, the extension 27 will be tensioned to a relatively high degree and the stretched wall 34 need only have the tension therein reduced by a relatively small amount before uncovering the opening 21, and in this position of the parts the pressure at which the diaphragm will move back in the position shown in Fig. 1 will be relatively low. Thus the above described structure is capable not only of producing pulsations, but it is also capable of accurately controlling these pulsations through a simple and automatic structure, and the time during which the diaphragm 25 is maintained in the position shown in Fig. 3 is easily regulated by the position of duct 20 and screw 29.

Figs. 4 and 5 illustrate a modified embodiment of the apparatus shown in Figs. 1 and 3 in positions respectively corresponding to those of Figs. 1 and 3. In the apparatus of Figs. 4 and 5, the casing 40 is formed with an opening 41 in which the neck of an apertured plate 42 similar to plate 22 is located. A tube 43 having opposite open ends is threadedly mounted in the internally threaded neck of plate 42. This apertured plate 42 is provided with flange 44 clamped between the flanges of the half shells of casing 40, and this flange 44 is formed with some of the apertures 45 which are distributed in the plate 42. Fixedly mounted on the flange 44 is a resilient diaphragm 46, which in the embodiment of Fig. 4 is substantially hemispherical in shape and has an inwardly extending annular flange fixed to the flange 45 by any suitable means, such as a ring 47 having screws passing therethrough, through the annular flange of diaphragm 46 and engaging threaded openings in the flange 45 of plate 42.

A dished wall 48 of resilient, stretchable material, which may be the same material as that of diaphragm 46, but may have a different thickness or may be a different material with different properties, is joined at its periphery to the underside of diaphragm 46, as shown in Fig. 4, the joint between elements 46 and 48 being carried out in any suitable way, such as by fusing elements 46 and 48 together in a manner well known in the plastics art. Thus, the member 48 forms with a part of the diaphragm 46 a gas enclosure similar to enclosure 33 described above, and the wall 48 has removably mounted thereon a plug 49 so that the pressure and gas within the enclosure 50 formed by diaphragm 46 and wall 48 may be regulated, when the plug 49 is removed, and kept in its regulated condition by replacing 49 so as to seal the enclosure 50. The plug 49 may be of any suitable construction. For example, an internally threaded ring 51 of relatively small diameter may be joined to the wall 48 and removably support the plug 49 which is externally threaded and in engagement with the threads of ring 51.

The tubular member 43 is located so that its lower open end is closed by diaphragm 46 when

the latter is in the position shown in Fig. 4 and opened when diaphragm 46 is shown in the position of Fig. 5. The pressure at which the diaphragm 46 will open the tube 43 to permit gas to enter the casing 40 may be regulated by turning of tube 43. Thus when the latter is adjusted in the position where its lower end, as viewed in Fig. 4, is located relatively near to the opening 41 of casing 40, the diaphragm 46 will only move through a relatively small distance before opening the tube 43 so that the pressure in casing 40 at which gas is admitted to the latter will be relatively high. However, when the lower end of tube 43, as viewed in Fig. 4, is located well within the casing 40 and at a substantially large distance from opening 41, the diaphragm 46 will necessarily move through a relatively large distance before uncovering the tube 43, and therefore the pressure in casing 40 will be relatively low before the vacuum therein is broken.

Also, by turning member 43 toward or away from enclosure 50, the space therein can be displaced to initially locate wall 48 respectively nearer to or farther from end 53 of duct 52 to provide an additional adjustment of the device.

The vacuum in casing 40 is produced by a duct 52 connected to a vacuum pump (not shown) and adjustably mounted on the casing 40 in the same way that duct 20 is mounted on casing 10, the only difference between ducts 20 and 52 being that the free open end 53 of the latter is not of a reduced cross-section. As the pressure in casing 40 is reduced by the suction in duct 52, the gas in enclosure 50 expands to cause the wall 48 to become distended toward the open end 53 of duct 52, this wall 48 closing opening 53 and being held over the latter by the suction in tube 52 until the gas pressure in casing 40 rises above a predetermined value in the same way as with the embodiment of Figs. 1 and 3. The adjustment of tube 52 in casing 40 controls the extent to which pressure rises in the casing 40, and with the embodiment of Fig. 4 the time when the tube 52 becomes closed may be regulated more accurately than with the embodiment of Figs. 1 and 3 because the gas in enclosure 50 may be independently controlled by changing the inside pressure.

A further embodiment of the invention is illustrated in Fig. 6, this embodiment combining an adjusting means similar to that of Figs. 1 and 3, for adjusting the tension in the resilient diaphragm, and the feature of Fig. 4 whereby the gas pressure within the gas enclosure may be regulated. The casing 60 and plate 61 of the structure of Fig. 6 are identical with the casing 40 and plate 42 of Fig. 4 except that the neck 62 of plate 61 is longer than the neck of plate 42 and is not internally threaded. This neck 62 is closed at its top by a plate 63 having a central aperture through which a rigid tube 64 extends, and the neck 62 is formed with a side opening in which the tube 65 is mounted to conduct gas to the interior of casing 60 through the neck 62 which forms a tubular means similar to tubular means 15, 23 of Figs. 1 and 3.

The diaphragm 66 is provided with an inwardly extending annular flange 67 mounted on the plate 61 in the same way that diaphragm 46 is mounted on plate 42. The top portion of the diaphragm 66 is provided with a resilient tubular extension 68 made of the same material as the diaphragm 66 and fixedly joined to the lower end portion of tube 64, as viewed in Fig. 6, by any suitable means such as the ring 69 which clamps the top end portion of extension 68 to the tube

64. If desired, extension 68 may be of a different thickness than diaphragm 66 or may be of a different stretchable material having different properties. The top end of the tube 64 is internally threaded and removably supports an externally threaded plug 70 which seals the extension 68 and tube 64 from the gas on the outside of casing 60. A wall 71 similar to wall 48, except that it is not provided with a removable plug, is joined to the underside of diaphragm 66, as shown in Fig. 6, so that this wall 71 forms together with the upper portion of diaphragm 66, extension 68 and tube 64 a gas enclosure 72, similar to the gas enclosures 33 and 50, which may have the gas therein controlled by removal of plug 70.

The sealing of the casing 60 is brought about by the resilient pressure of diaphragm 66 against the lower end of neck 62. A collar 73 is mounted about the tube 64 and fixed at a predetermined position along the length thereof by means of a set screw 74, this collar 73 being maintained against the cover 63 of neck 62 by the resilient force of the diaphragm 66 with its extension 68. Thus, by locating the collar 73 nearer to the lower end of tube 64, as viewed in Fig. 6, the tension in extension 68 and diaphragm 66 may be increased in the same way that the tension in extension 27 of diaphragm 25 is regulated by turning of screw 29, in the embodiment illustrated in Figs. 1 and 3, so as to vary the force with which the diaphragm 66 bears against the lower end of neck 62 to close the latter and seal the interior of casing 60.

The suction duct 75 is adapted to be connected to a vacuum pump (not shown) for producing a partial vacuum within the casing 60, and is adjustably mounted in the same way as duct 52 to cooperate with wall 71 in the manner described above, the gas in enclosure 72 expanding and contracting to distend the wall 71 which covers and uncovers the open free end 76 of duct 75 in the same way as in the embodiments described above. The embodiment of Fig. 6 operates in exactly the same way as in the above described embodiments of the invention to produce the same results.

It will be noted that in all of the above-described embodiments the resilient diaphragms are removably mounted so as to be exchangeable with other diaphragms. In this way any of the above-described embodiments may be provided with diaphragms of different properties and/or materials suited for a particular use to which the invention is applied.

It will be understood that each of the elements described above, or two or more together, may also find a useful application in other types of vacuum breakers differing from the types described above.

While the invention has been illustrated and described as embodied in adjustable vacuum breakers, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention, and therefore, such adaptations should

and are intended to be comprehended within the meaning and range of equivalence of the following claims.

What is claimed as new and desired to be secured by Letters Patent is:

1. Vacuum breaking apparatus, comprising, in combination, a hollow casing formed with an opening in a wall thereof; automatic valve means associated with said opening and being mounted on said casing for automatic movement between a closing position preventing the passage of gas through said opening and an open position permitting the passage of gas through said opening, said valve means being automatically movable into said open position when gas pressure in said casing decreases below a first predetermined value and said valve means including a resilient portion urging the same into said closing position thereof when the gas pressure in said casing rises above said first predetermined value; duct means communicating with said casing and adapted to be connected to a vacuum pump for reducing the gas pressure in said casing below said first predetermined value so as to produce a partial vacuum in said casing and cause said valve means to automatically move against the action of said resilient portion thereof into said open position; and pressure sensitive closure means communicating with the interior of said casing to be actuated by the pressure therein, and connected to said automatic valve means for movement therewith, and being associated with said duct means to close the same when said valve means is in said open position thereof and to maintain said duct means closed and said valve means in said open position until the gas pressure in said casing rises above a second predetermined value higher than said first predetermined value, said resilient portion of said automatic valve means moving the latter into said closed position thereof when the gas pressure in said casing rises above said second predetermined value.

2. Vacuum breaking apparatus, comprising, in combination, a hollow casing formed with an opening in a wall thereof; automatic valve means associated with said opening and being mounted on said casing for automatic movement between a closing position preventing the passage of gas through said opening and an open position permitting the passage of gas through said opening, said valve means being automatically movable into said open position when gas pressure in said casing decreases below a first predetermined value and said valve means including a resilient portion urging the same into said closing position thereof when the gas pressure in said casing rises above said first predetermined value; duct means communicating with said casing and adapted to be connected to a vacuum pump for reducing the gas pressure in said casing below said first predetermined value so as to produce a partial vacuum in said casing and cause said valve means to automatically move against the action of said resilient portion thereof into said open position; pressure sensitive closure means communicating with the interior of said casing to be actuated by the pressure therein, and connected to said automatic valve means for movement therewith, and being associated with said duct means to close the same when said valve means is in said open position thereof and to maintain said duct means closed and said valve means in said open position until the gas pressure in said casing rises above

a second predetermined value higher than said first predetermined value, said resilient portion of said automotive valve means moving the latter into said closed position thereof when the gas pressure in said casing rises above said second predetermined value; and adjusting means connected to said valve means for setting said first predetermined value.

3. Vacuum breaking apparatus, comprising, in combination, a hollow casing; first duct means communicating with the interior of said casing to convey gas to the same; a resilient diaphragm supported in said casing with a portion thereof spaced from said casing and forming therewith a passage for gas from said first duct means into the interior of said casing, said diaphragm being located over said first duct means to close the same and being movable away from said first duct means to open the same; second duct means having a free open end in the interior of said casing and being adapted to be connected to a vacuum pump for producing a partial vacuum in said casing to cause said diaphragm to automatically move away from and open said first duct means when the pressure in said casing falls below a predetermined value; a flexible resilient enclosure having a wall thereof joined to said diaphragm and facing said free open end of said second duct means, said enclosure trapping a gas between itself and said diaphragm so that, when the gas in said enclosure expands and said diaphragm moves away from said first duct means, said wall of said enclosure moves toward and covers said second duct means.

4. Vacuum breaking apparatus, comprising, in combination, a hollow casing; first duct means communicating with the interior of said casing to convey gas to the same; a resilient diaphragm supported in said casing with a portion thereof spaced from said casing and forming therewith a passage for gas from said first duct means into the interior of said casing, said diaphragm being located over said first duct means to close the same and being movable away from said first duct means to open the same; second duct means having a free open end in the interior of said casing on the opposite side of said diaphragm from said first duct means, said second duct means being adapted to be connected to a vacuum pump for producing a partial vacuum in said casing to cause said diaphragm to automatically move away from and open said first duct means when the pressure in said casing falls below a predetermined value; a flexible resilient enclosure having a wall thereof joined to said diaphragm and facing said free open end of said second duct means, said enclosure trapping a gas between itself and said diaphragm so that, when the gas in said enclosure expands and said diaphragm moves away from said first duct means, said wall of said enclosure moves toward and covers said second duct means.

5. Vacuum breaking apparatus, comprising, in combination, a hollow casing; first duct means communicating with the interior of said casing to convey gas to the same; a plate fixedly mounted in said casing and having a portion extending into said casing and formed with an opening passing therethrough; a resilient diaphragm supported on said plate in said casing away from said opening in said plate, said diaphragm having a portion thereof spaced from said casing and forming therewith a passage for gas from said first duct means into the interior of said casing, said diaphragm being located over said first

duct means to close the same and being movable away from said first duct means to open the same; second duct means having a free open end in the interior of said casing on the opposite side of said diaphragm from said first duct means, said second duct means being adapted to be connected to a vacuum pump for producing a partial vacuum in said casing to cause said diaphragm to automatically move away from and open said first duct means when the pressure in said casing falls below a predetermined value; a flexible resilient enclosure having a wall thereof joined to said diaphragm and facing said free open end of said second duct means, said enclosure trapping a gas between itself and said diaphragm so that, when the gas in said enclosure expands and said diaphragm moves away from said first duct means, said wall of said enclosure moves toward and covers said second duct means.

6. Vacuum breaking apparatus as defined in claim 5 and wherein said second duct means is adjustably mounted on said casing so that said free open end thereof may be located at a predetermined distance from said wall of said enclosure.

7. Vacuum breaking apparatus as defined in claim 5 and wherein a plug is removably mounted on said wall of said enclosure so that the gas therein may be controlled.

8. Vacuum breaking apparatus as defined in claim 5 and wherein part of said enclosure is formed by a portion of said diaphragm located opposite said wall of said enclosure.

35 9. Vacuum breaking apparatus as defined in claim 5 and wherein said resilient diaphragm is removably mounted on said plate so that one diaphragm may be exchanged for another.

10. Vacuum breaking apparatus, comprising, in combination, a hollow casing formed with an opening passing therethrough; tubular means joined to said opening of said casing for conveying gas to the interior thereof; a plate fixedly mounted in said casing distant from said tubular means and being formed with an aperture passing therethrough; a resilient, flexible diaphragm fixedly mounted on said plate, away from said aperture thereof, in the interior of said casing and resiliently pressing against said tubular means to close the same, said diaphragm having an extension projecting into said tubular means; duct means communicating with the interior of said casing and being adapted to be connected to a vacuum pump for producing a partial vacuum in said casing, said duct means having a free open end located adjacent to said diaphragm on the opposite side thereof from said tubular means; and a gas enclosure having a wall thereof joined to said diaphragm and located opposite said free open end of said duct means.

11. Vacuum breaking apparatus, comprising, in combination, a hollow casing formed with an opening passing therethrough; tubular means joined to said opening of said casing for conveying gas to the interior thereof; a plate fixedly mounted in said casing distant from said tubular means and being formed with an aperture passing therethrough; a resilient, flexible diaphragm fixedly mounted on said plate, away from said aperture thereof, in the interior of said casing and resiliently pressing against said tubular means to close the same, said diaphragm having an extension projecting into said tubular means; duct means communicating with the interior of said casing and being adapted to be

11

connected to a vacuum pump for producing a partial vacuum in said casing, said duct means having a free open end located adjacent to said diaphragm on the opposite side thereof from said tubular means; and a gas enclosure having a wall thereof joined to said diaphragm and located opposite said free open end of said duct means, said gas enclosure being partly formed from a portion of said diaphragm located opposite said wall of said enclosure.

12. Vacuum breaking apparatus, comprising, in combination, a hollow casing formed with an opening passing therethrough; tubular means joined to said opening of said casing for conveying gas to the interior thereof; a plate fixedly mounted in said casing distant from said tubular means and being formed with an aperture passing therethrough; a resilient, flexible diaphragm fixedly mounted on said plate, away from said aperture thereof, in the interior of said casing and resiliently pressing against said tubular means to close the same, said diaphragm having an extension projecting into said tubular means; duct means communicating with the interior of said casing and being adapted to be connected to a vacuum pump for producing a partial vacuum in said casing, said duct means having a free open end located adjacent to said diaphragm on the opposite side thereof from said tubular means; a gas enclosure having a wall thereof joined to said diaphragm and located opposite said free open end of said duct means, said gas

5

enclosure being partly formed from a portion of said diaphragm located opposite said wall of said enclosure; and adjusting means mounted on said tubular means and being operatively connected to said extension of said diaphragm to adjust the tension therein and thereby adjust the force with which said diaphragm bears against said tubular means.

13. Vacuum breaking apparatus as defined in claim 10 and wherein said extension of said diaphragm is hollow and communicates with the interior of said gas enclosure.

14. Vacuum breaking apparatus as defined in claim 13 and wherein a closure means is associated with said hollow extension of said diaphragm to open and close the same for controlling the gas in said gas enclosure.

15. Vacuum breaking apparatus as defined in claim 10 and wherein said duct means is adjustably mounted on said casing so that said free open end of said duct means may be located at a predetermined distance from said wall of said enclosure.
